Roger C. Hahn**CLAIM**

We claim the ornamental design for a water supply for a dialysis cabinet, as shown and described.

DESCRIPTION

FIG. 1 is a perspective view showing our new design for a water supply for a dialysis cabinet;

FIG. 2 is another perspective view thereof;

FIG. 3 is a front view of the water supply of the dialysis cabinet referenced in FIG. 2;

FIG. 4 is a rear view of the water supply of the dialysis cabinet referenced in FIG. 2;

FIG. 5 is a left side view of the water supply of the dialysis cabinet referenced in FIG. 2;

FIG. 6 is a right side view of the water supply of the dialysis cabinet referenced in FIG. 2;

FIG. 7 is a top side view of the water supply of the dialysis cabinet referenced in FIG. 2; and,

FIG. 8 is a bottom view of the water supply of the dialysis cabinet referenced in FIG. 2.

In the drawings, the broken lines depict environmental subject matter only and form no part of the claimed design.
